Patented Dec. 14, 1965

203,206

COMBINED WATER AND PLANT FERTILIZER APPLICATOR

Joseph Cefalde, 29 Miliit Ave., Youngstown, Ohio

Filed June 24, 1964, Ser. No. 80,559

Term of patent 14 years

(Cl. D35—1)

FIGURE 1 is a perspective view showing the front, the top and one side of a combined water and plant fertilizer applicator, showing my new design;

FIGURE 2 is a perspective view showing the back, bottom and the other side thereof.

I claim:

The ornamental design for a combined water and plant fertilizer applicator, as shown.
